ENGAGEMENT ARTICLE, LOAD POSITIONING SYSTEM, AND PROCESS FOR POSITIONING LOADS

FIELD OF THE INVENTION

The present invention relates to an engagement article for selectively restricting motion of an article. More specifically, the present invention relates to a braking system for selectively restricting motion of an article.

BACKGROUND OF THE INVENTION

Loads positioned and repositioned within a system are often subjected to forces that can result in undesirable movement or safety concerns, for example, when a suspended load is moved laterally along a system, using a shuttle or cart along a track. It is known to suspend loads from moving shuttles, carriages, or carts in an effort to provide a theatrical or aesthetic effect, such as flying performers through a three dimensional space. These loads are frequently raised and lowered utilizing cables, wires or ropes deployed or retracted from a remote location. One challenge in maintaining safe operation of the shuttle, carriage, or cart is maintaining the position of the suspended load in the event of a partial or complete failure of the control system for the carriage. For example, a carriage controlled by wires may experience wire breakage wherein the load causes rapid or uncontrolled lateral motion of the shuttle and a rapid lowering of the load.

An article, system, and process capable of selectively restricting movement and/or capable of securing a load in response to a rapid change in tension in one or more lines would be desirable in the art.

SUMMARY OF THE INVENTION

In an exemplary embodiment, an engagement article is capable of selectively restricting movement or is capable of securing a load in response to a rapid change in tension in one or more lines.

In another exemplary embodiment, a system includes an engagement article capable of selectively restricting movement or securing a load in response to a rapid change in tension in one or more lines.

In another exemplary embodiment, process of selectively restricting movement or securing a suspended load includes providing an engagement article in response to a rapid change in tension in one or more lines and actuating the engagement article.

Other features and advantages of the present invention will be apparent from the following more detailed description of the preferred embodiment, taken in conjunction with the accompanying drawings which illustrate, by way of example, the principles of the invention.

BRIEF DESCRIPTION OF THE DRAWINGS

FIG. 1 shows a side schematic view of an exemplary system according to the disclosure.

FIG. 2 shows a side schematic view of an exemplary engagement article permitting movement according to the disclosure.

FIG. 3 shows a side schematic view of an exemplary engagement article restricting, but not stopping movement according to the disclosure.

2

FIG. 4 shows a side schematic view of an exemplary engagement article restricting and stopping movement according to the disclosure.

FIG. 5 shows a side schematic view of an exemplary system according to the disclosure.

FIG. 6 shows an end schematic view of an exemplary system according to the disclosure.

FIG. 7 shows an end schematic view of an exemplary system according to the disclosure.

FIG. 8 shows a side schematic view of an exemplary system with dual engagement articles according to the disclosure.

FIG. 9 shows an end schematic view of an exemplary system according to the disclosure.

FIGS. 10, 10A and 10B show side schematic views of respective exemplary engagement articles according to the disclosure.

FIG. 11 shows a perspective view of dual lever assemblies for an exemplary engagement article according to the disclosure.

FIG. 12 shows an end schematic view of an exemplary system according to the disclosure.

FIG. 13 shows a side schematic view of an exemplary engagement article according to the disclosure.

Wherever possible, the same reference numbers will be used throughout the drawings to represent the same parts.

DETAILED DESCRIPTION OF THE INVENTION

30 Provided is an engagement article, a system including the engagement article, and a process of selectively actuating the engagement article to restrict movement of a carriage. Embodiments of the present disclosure are capable of selectively restricting movement, capable of securing a load (for example, in response to a rapid change in tension in one or more lines), capable of positioning and repositioning loads, capable of permitting coordinated movements of loads on a stage according to a predetermined program, and combinations thereof.

40 FIG. 1 shows a system 100 according to the disclosure. In one embodiment, the system 100 includes at least one support member 102, at least one carriage 104, at least one load 106, at least one travel line 108, at least one lift line 110, a travel positioning mechanism 112, a lift positioning mechanism 114 operatively connected to each other, and at least one control system 116 to control system 100. The system 100 is configured to position and reposition a load 106 by movement of the travel line 108, the lift line 110, the travel positioning mechanism 112, the lift positioning mechanism 114, and the carriage 104, along the support member 102 according to a program executed by the control system 116.

In one embodiment, the support member 102 is a beam or other suitable member (for example, a track, a rail, a truss or a pipe) capable of providing structural support for the carriage

55 104 (or a suspended shuttle or cart or trolley or tram or any other apparatus capable of moving along the support member and being capable of supporting the load). In one embodiment, the support member 102 is mounted above a stage, exhibit, or theatrical area (not shown). In another embodiment, the system includes multiple support members 102 mounted at various angles (for example, about 0 degrees, about 5 degrees, about 10 degrees, about 15 degrees or about 30 degrees, or any suitable range or sub-range thereof) relative to the stage, exhibit, or theatrical area. In another embodiment, a plurality of the support members 102 are mounted at various angles relative to each other (for example, about 0

60 degrees, 5 degrees, 10 degrees, 15 degrees, 30 degrees, about 45 degrees, 60 degrees, 75 degrees, 90 degrees, 105 degrees, 120 degrees, 135 degrees, 150 degrees, 165 degrees, 180 degrees, 195 degrees, 210 degrees, 225 degrees, 240 degrees, 255 degrees, 270 degrees, 285 degrees, 300 degrees, 315 degrees, 330 degrees, 345 degrees, 360 degrees, 375 degrees, 390 degrees, 405 degrees, 420 degrees, 435 degrees, 450 degrees, 465 degrees, 480 degrees, 495 degrees, 510 degrees, 525 degrees, 540 degrees, 555 degrees, 570 degrees, 585 degrees, 600 degrees, 615 degrees, 630 degrees, 645 degrees, 12425 degrees, 12440 degrees, 12455 degrees, 12470 degrees, 12485 degrees, 12495 degrees, 12510 degrees, 12525 degrees, 12540 degrees, 12555 degrees, 12570 degrees, 12585 degrees, 12595 degrees, 12610 degrees, 12625 degrees, 12640 degrees, 12655 degrees, 12670 degrees, 12685 degrees, 12695 degrees, 12710 degrees, 12725 degrees, 12740 degrees, 12755 degrees, 12770 degrees, 12785 degrees, 12795 degrees, 12810 degrees, 12825 degrees, 12840 degrees, 12855 degrees, 12870 degrees, 12885 degrees, 12895 degrees, 12910 degrees, 12925 degrees, 12940 degrees, 12955 degrees, 12970 degrees, 12985 degrees, 12995 degrees, 13010 degrees, 13025 degrees, 13040 degrees, 13055 degrees, 13070 degrees, 13085 degrees, 13095 degrees, 13110 degrees, 13125 degrees, 13140 degrees, 13155 degrees, 13170 degrees, 13185 degrees, 13195 degrees, 13210 degrees, 13225 degrees, 13240 degrees, 13255 degrees, 13270 degrees, 13285 degrees, 13295 degrees, 13310 degrees, 13325 degrees, 13340 degrees, 13355 degrees, 13370 degrees, 13385 degrees, 13395 degrees, 13410 degrees, 13425 degrees, 13440 degrees, 13455 degrees, 13470 degrees, 13485 degrees, 13495 degrees, 13510 degrees, 13525 degrees, 13540 degrees, 13555 degrees, 13570 degrees, 13585 degrees, 13595 degrees, 13610 degrees, 13625 degrees, 13640 degrees, 13655 degrees, 13670 degrees, 13685 degrees, 13695 degrees, 13710 degrees, 13725 degrees, 13740 degrees, 13755 degrees, 13770 degrees, 13785 degrees, 13795 degrees, 13810 degrees, 13825 degrees, 13840 degrees, 13855 degrees, 13870 degrees, 13885 degrees, 13895 degrees, 13910 degrees, 13925 degrees, 13940 degrees, 13955 degrees, 13970 degrees, 13985 degrees, 13995 degrees, 14010 degrees, 14025 degrees, 14040 degrees, 14055 degrees, 14070 degrees, 14085 degrees, 14095 degrees, 14110 degrees, 14125 degrees, 14140 degrees, 14155 degrees, 14170 degrees, 14185 degrees, 14195 degrees, 14210 degrees, 14225 degrees, 14240 degrees, 14255 degrees, 14270 degrees, 14285 degrees, 14295 degrees, 14310 degrees, 14325 degrees, 14340 degrees, 14355 degrees, 14370 degrees, 14385 degrees, 14395 degrees, 14410 degrees, 14425 degrees, 14440 degrees, 14455 degrees, 14470 degrees, 14485 degrees, 14495 degrees, 14510 degrees, 14525 degrees, 14540 degrees, 14555 degrees, 14570 degrees, 14585 degrees, 14595 degrees, 14610 degrees, 14625 degrees, 14640 degrees, 14655 degrees, 14670 degrees, 14685 degrees, 14695 degrees, 14710 degrees, 14725 degrees, 14740 degrees, 14755 degrees, 14770 degrees, 14785 degrees, 14795 degrees, 14810 degrees, 14825 degrees, 14840 degrees, 14855 degrees, 14870 degrees, 14885 degrees, 14895 degrees, 14910 degrees, 14925 degrees, 14940 degrees, 14955 degrees, 14970 degrees, 14985 degrees, 14995 degrees, 15010 degrees, 15025 degrees, 15040 degrees, 15055 degrees, 15070 degrees, 15085 degrees, 15095 degrees, 15110 degrees, 15125 degrees, 15140 degrees, 15155 degrees, 15170 degrees, 15185 degrees, 15195 degrees, 15210 degrees, 15225 degrees, 15240 degrees, 15255 degrees, 15270 degrees, 15285 degrees, 15295 degrees, 15310 degrees, 15325 degrees, 15340 degrees, 15355 degrees, 15370 degrees, 15385 degrees, 15395 degrees, 15410 degrees, 15425 degrees, 15440 degrees, 15455 degrees, 15470 degrees, 15485 degrees, 15495 degrees, 15510 degrees, 15525 degrees, 15540 degrees, 15555 degrees, 15570 degrees, 15585 degrees, 15595 degrees, 15610 degrees, 15625 degrees, 15640 degrees, 15655 degrees, 15670 degrees, 15685 degrees, 15695 degrees, 15710 degrees, 15725 degrees, 15740 degrees, 15755 degrees, 15770 degrees, 15785 degrees, 15795 degrees, 15810 degrees, 15825 degrees, 15840 degrees, 15855 degrees, 15870 degrees, 15885 degrees, 15895 degrees, 15910 degrees, 15925 degrees, 15940 degrees, 15955 degrees, 15970 degrees, 15985 degrees, 15995 degrees, 16010 degrees, 16025 degrees, 16040 degrees, 16055 degrees, 16070 degrees, 16085 degrees, 16095 degrees, 16110 degrees, 16125 degrees, 16140 degrees, 16155 degrees, 16170 degrees, 16185 degrees, 16195 degrees, 16210 degrees, 16225 degrees, 16240 degrees, 16255 degrees, 16270 degrees, 16285 degrees, 16295 degrees, 16310 degrees, 16325 degrees, 16340 degrees, 16355 degrees, 16370 degrees, 16385 degrees, 16395 degrees, 16410 degrees, 16425 degrees, 16440 degrees, 16455 degrees, 16470 degrees, 16485 degrees, 16495 degrees, 16510 degrees, 16525 degrees, 16540 degrees, 16555 degrees, 16570 degrees, 16585 degrees, 16595 degrees, 16610 degrees, 16625 degrees, 16640 degrees, 16655 degrees, 16670 degrees, 16685 degrees, 16695 degrees, 16710 degrees, 16725 degrees, 16740 degrees, 16755 degrees, 16770 degrees, 16785 degrees, 16795 degrees, 16810 degrees, 16825 degrees, 16840 degrees, 16855 degrees, 16870 degrees, 16885 degrees, 16895 degrees, 16910 degrees, 16925 degrees, 16940 degrees, 16955 degrees, 16970 degrees, 16985 degrees, 16995 degrees, 17010 degrees, 17025 degrees, 17040 degrees, 17055 degrees, 17070 degrees, 17085 degrees, 17095 degrees, 17110 degrees, 17125 degrees, 17140 degrees, 17155 degrees, 17170 degrees, 17185 degrees, 17195 degrees, 17210 degrees, 17225 degrees, 17240 degrees, 17255 degrees, 17270 degrees, 17285 degrees, 17295 degrees, 17310 degrees, 17325 degrees, 17340 degrees, 17355 degrees, 17370 degrees, 17385 degrees, 17395 degrees, 17410 degrees, 17425 degrees, 17440 degrees, 17455

45 degrees or any suitable range or sub-range thereof), stacked, positioned parallel, intersecting, or positioned in any suitable combination thereof.

The support member 102 is any suitable geometry. In one embodiment, the support member 102 is a substantially straight, elongate member. In another embodiment, the support member 102 is curved, or has curved portions. In one embodiment, the support member 102 is segmented, including connector members (not shown) joining the various segments. Alternatively, the support member 102 is of unitary construction.

The load 106 is any suitable object capable of being positioned and repositioned relative to the stage, exhibit, or theatrical area. Suitable loads include, but are not limited to, performers, equipment, instruments, props, lights, lighting systems, cameras, scenery, sets, microphones, speakers in combinations thereof.

The travel line 108 and the lift line 110 are elongate members such as cables, rope, cord, band or chain-links, or any suitable combination thereof. In one embodiment, the system 100 further includes one or more additional support guides (not shown) for supporting the lift line 110 securely in its travel path as the carriage 104 moves along the support member 102. The travel line 108 and the lift line 110 are control elements that provide motion and positioning to the carriage 104 and/or the load 106. In one embodiment, the travel line 108 is operatively connected to the carriage 104 and to travel positioning mechanism 112. When actuated, the travel positioning mechanism(s) 112 controls or adjusts the position, speed, and acceleration or deceleration of the carriage 104 along the support member 102. Travel positioning mechanism 112 controls the travel line 108 operation, enabling carriage 104 to be moved, positioned, and repositioned along support member 102. The lift line 110 is operatively connected through carriage 104 to the load 106 and to the lift positioning mechanism 114. The lift positioning mechanism 114 controls the lift line 110 operation in simultaneous coordination with the travel line 108 operation, enabling load 106 to be positioned and repositioned as carriage 104 is positioned and repositioned along support member 102.

The lift positioning mechanism 114 controls or adjusts the position, speed, and acceleration or deceleration of the load 106 relative to the carriage 104. The travel positioning mechanism 112 controls or adjusts the position, speed, and acceleration or deceleration of the carriage 104 relative to the support member 102. In one embodiment, one or more of the travel positioning mechanism(s) 112, and the lift positioning mechanism 114 is an automated device, such as a variable control or computer controlled winch. In another embodiment, one or more of the travel positioning mechanism(s) 112 and the lift positioning mechanism 114 is a manual device capable of rotatably extending or retracting the travel line 108 and/or the lift line 110. The term manual device means that neither variable control nor computer control is utilized for the device to operate. In a further embodiment, the travel positioning mechanism 112 and the lift positioning mechanism 114 is a combination of a manual device and an automated device.

In one embodiment, the carriage 104 includes a cart 118, an engagement article such as a cam brake 120, and a load mount 122. The cart 118 includes a cart frame 124 and a plurality of wheels or rollers 126. The cart frame 124 includes a travel line connection 128 on one end, a cam brake connection 130 on an opposite end, and a load mounting member connection 132 positioned proximal to the load 106. The plurality of wheels or rollers 126 is configured to engage, roll, and/or slide along an engagement surface 134 of the support member 102,

enabling the cart 118 and carriage 104 to move along the support member 102. In one embodiment, a first end 136 of the travel line 108 is operatively connected to the travel line 108 connection 128 of the cart frame 124 and a second end 138 of the travel line 108 is operatively connected to the cam brake 120.

The load mount 122 includes at least one pulley or sheave 123, a pulley frame 127, and a pivot shaft 129. The pulley frame 127 attaches to the load mounting member connection 132 of the cart frame 124. The pulley or sheave 123 is rotatably mounted to the pulley frame 127 with the pivot shaft 129. The pulley or sheave 123 is configured to engage the lift line 110 to position the load 106. A first end 107 of the lift line 110 is connected to the load 106, and a second end 111 is connected to the lift positioning mechanism 114.

As shown in FIGS. 2-4, in one embodiment, the cam brake 120 includes a weighted member 140, a cam engagement member 142, a frame 143, and a cam pivot member 144. In one embodiment, cam engagement member 142 and weighted member 140 are of the unitary construction. In one embodiment, an optional airflow interaction feature 154 may be formed in one or more of weighted member 140 and cam engagement feature 142 to facilitate rotation of the cam engagement member 142 about cam pivot member 144. In a further embodiment, airflow interaction feature 154 may be utilized in combination with or as a substitute for weighted member 140, in which case the airflow interaction feature 154 would only be formed in cam engagement feature 142. The cam pivot member 144 is pivotally connected to the cam engagement member 142 eccentrically with respect to the center of gravity of the cam engagement member 142. For example, this eccentric mounting enables the cam engagement member 142 to be rotated about cam pivot member 144 into and out of a position of engagement with support member 102, by the displacement of weighted member 140 (or by virtue of airflow interaction feature(s) 154 interacting with slower moving air surrounding the cam engagement member 142 having the airflow interaction feature(s)).

As used herein, airflow interaction feature 154 may be used as an airfoil to provide an upwardly directed force also referred to as lift, or as a "spoiler" to provide a downwardly directed force, such as used with top fuel dragsters to maintain traction between the tires and the road surface. That is, factors such as the location of airflow interaction feature 154 relative to cam pivot member 144 and the desired magnitude and direction of airflow-induced forces withstood by airflow interaction feature 154 over the range of angular movement of cam pivot member 144 as a function of velocity of the carriage may be considered in order to determine the shape and/or orientation of the airflow interaction feature.

In one embodiment, a first portion 146 of the weighted member 140 is connected to the cam engagement member 142 at the cam pivot member 144. A second portion 148 of the weighted member 140 is connected to the second end 138 of the travel line 108. In one embodiment, the center of gravity of the weighted member 140 is located at the second portion 148, or closer to the second portion 148 than the first portion 146, proximal to the connection of the travel line 108.

Referring to FIGS. 9-11, in one embodiment, the carriage 104 includes the cart 118, the cam brake 120, and the load mount 122. In this embodiment, the cart 118 includes the cart frame 124 and the plurality of wheels or rollers 126. The cam brake 120 includes first lever assembly 240, second lever assembly 241, the cam engagement member 142, and the cam pivot member 144. Each of first lever assembly 240 and second lever assembly 241 includes a lever pivot 244 and a

pair of weighted members 140 with a travel line connection 248. The cam engagement member 142 includes a pair of opposing limit stops 249.

In one embodiment, the cam engagement member 142 pivotally connects to the cart frame 124 via the cam pivot member 144. In one embodiment, the pair of the weighted members 140 pivotally connects at their first portions 146 to the cam engagement member 142 via the lever pivot 244. In one embodiment, optional airflow interaction feature 154 may be utilized in combination with or as a substitute for weighted member 140, in which case the airflow interaction feature 154 would only be formed in cam engagement feature 142. In one embodiment, cam engagement member 142 may employ airflow interaction feature 154, a biasing device 167 (FIG. 1), weighted member 140 or a combination thereof.

In one embodiment, the travel line connection 248 connects to the second portion 148 of the weighted member 140. The first lever assembly 240 connects to the first end 136 of the travel line 108, and the second lever assembly 241 connects to the second end 138 of the travel line 108.

In one embodiment, the travel line 108 forms a loop (not shown) that engages one or more of the travel positioning mechanisms 112, enabling the carriage 104 to be moved in either direction along the support member 102.

As shown in FIG. 10B, travel line connections 160 formed in cam engagement feature 142 are arranged relative to cam pivot member 144 such that line-of-force spacing 156 is maintained between cam pivot member 144 and either travel line connection 160, even after cam engagement feature 142 is rotated into contact with support structure 102. With such an arrangement, in the case of a sudden loss of tension of travel line 108 formerly pulling a carriage (not shown) connected to cam engagement feature 142, residual tension in the opposed travel line 108 directed opposite travel direction 158 would further result, at least initially, in urging cam engagement feature 142 in a clockwise direction, and could supplement other similarly directed forces, such as forces associated with airflow interaction feature 154.

As further shown in FIG. 10A, limit stops 249 position first and second lever assemblies 240, 241 such that forces generated in by airflow interaction devices 154 are maximized in a direction opposite the travel direction of the carriage to decelerate or stop the carriage, and supplemented by optional airflow interaction devices 154 formed in cam engagement feature 142. That is, limit stops 249 associated with first and second lever assemblies 240, 241 can orient the lever assembly pointing in a direction opposite that of carriage travel such that airflow forces associated with airflow interaction features further supplement forces applied to secure cam engagement feature 142 in frictional contact with support member 102.

Referring again to FIG. 1, in one embodiment, the control system 116 includes computers or microprocessors (not shown), and/or other suitable control devices. In one embodiment, the control system 116 includes remote-control capabilities, various suitable user interfaces, and communication between the remote-control devices and/or user interfaces and the travel positioning mechanism 112 and/or lift positioning mechanism 114. In one embodiment, the travel positioning mechanism 112 and/or lift positioning mechanism 114 include suitable power and control devices such as servomotors (not shown) and position encoders (not shown). In one embodiment, the control of a predetermined movement or positioning sequence of the carriage 104 and load 106 is enacted according to a control program using algorithms or other suitable means. For example, the user may require raising the load 106 at a first predetermined rate (such as two feet per second) as the carriage 104 moves from left to right

along support member 102 at a second predetermined rate (such as one foot per second). To raise the load 106, the control program initiates coordinated retraction movement of the lift line 110 and the travel line 108, incorporating feedback from the position encoders to control the servomotors. In one embodiment, the position of the lift line 110 and the vertical position of the load 106 are varied by the control system 116 as the carriage 104 moves along the support member 102. In one embodiment, the control system 116 is capable of maintaining a constant elevation of the load 106 as the carriage 104 moves along the support member 102.

The control system 116 communicates (for example, transmits and/or receives signals and/or data) with and adjusts the lift positioning mechanism(s) 114 and travel positioning mechanism(s) 112 to coordinate the position of the load 106. Control communication includes wireless (infrared (IR), radio frequency (RF), etc.), wired/electrical, mechanical (distance measuring of line), and sensors (position, weight, speed, vibration, acoustic; acoustic being used for keeping operation below a predetermined sound level while moving as fast as possible).

The control system 116 communicates with and adjusts the travel positioning mechanism(s) 112 to maintain the cam brake 120 in a full tension position such that the cam engagement member 142 is held out a predetermined range of distance from the support member 102 surface.

Referring collectively to FIGS. 3 and 4, the cam engagement member 142 includes upper portion 150 and top section 152. An external portion of upper portion 150 and top section 152 is configured to engage the support member 102. In one embodiment, the external portions of upper portion 150 and/or top section 152 are serrated, knurled, grooved, or at least partially define a geared surface having protruding or recessed teeth corresponding to the mating surface of the support member 102. Additionally or alternatively, the external portions of upper portion 150 and/or top section 152 include geometry capable of selectively engaging the surface of the support member 102. In one embodiment, the system 100 includes brake pads or shoes positioned on the cam engagement member 142 to frictionally engage the support member 102. In one embodiment, the control system 116 includes sensors (not shown) that determine when the cam engagement member 142 has engaged the support member 102, and the control system 116 uses this status to signal or otherwise initiate other control operations, such as deactivating motors associated with one or more of the lift positioning mechanism(s) 114 and travel positioning mechanism(s) 112 and alerting an operator. The position of the cam engagement member 142 relative to the support member 102 resulting in frictional engagement is controlled by the control system 116 to provide a predetermined deceleration or braking of the carriage 104. In another embodiment, a purely mechanical linkage may be actuated to selectively position cam member 142 relative to the support member 102, resulting in a predetermined frictional engagement, which engagement may or may not be a function of an operating parameter, such as the velocity of the carriage.

The control system 116 adjusts the travel positioning mechanism(s) 112 to maintain the cam brake 120 in deceleration position by producing slack at the second end 138 of the travel line 108, causing the weighted member 140 of the cam brake 120 to actuate due to gravity and rotate the cam engagement member 142 about the cam pivot member 144. Alternatively, slack at the second end 138 of the travel line 108 occurs due to a rapid change or failure of one or more control elements such as a rapid change in tension in one or more lines, (for example, upon breaking of the travel line 108

proximal to the second end 138). As shown in FIG. 3, the slack enables an upper portion 150 of the cam engagement member 142 to frictionally engage the support member 102 surface to cause deceleration of the carriage 104. Thereafter, increasing tension at the second end 138 of the travel line 108 causes the weighted member 140 of the cam brake 120 to rise and rotate the cam engagement member 142 about the cam pivot member 144 in the opposite direction, disengaging the cam engagement member 142 from the support member 102 surface, and freeing the carriage 104 for movement along the support member 102. In one embodiment, the control system 116 sensors (not shown) determine when the cam engagement member 142 has fully disengaged the support member 102, and the control system 116 uses this status to signal other control operations, such as activating motors associated with the lift positioning mechanism(s) 114 and travel positioning mechanism(s) 112 and alerting an operator.

Referring to FIGS. 9-11, in one embodiment, when the carriage 104 is moving in a first direction along the support member 102, the control system 116 produces slack at the second end 138 of the travel line 108 to cause deceleration or stopping of the carriage 104. Alternatively, slack at the second end 138 of the travel line 108 occurs due to a rapid change in tension in one or more lines in the system. When the carriage 104 is moving in a second direction along the support member 102, the control system 116 produces slack at the first end 136 of the travel line 108 to cause deceleration or stopping of the carriage 104. Alternatively, slack at the first end 136 of the travel line 108 occurs due to wear and/or deterioration in the system, (for example, upon the travel line 108 proximal to the second end 138 breaking).

Referring collectively to FIGS. 12-13, cam engagement member 142 includes a position retention feature 162 for engaging a mating feature 164 formed in support member 102 in special circumstances, such as when tension in opposed travel lines 108 is simultaneously removed by an operator, or if automated, by the system. In this circumstance, engagement between retention feature 162 and mating feature 164 ensures the carriage does not move relative to the support member 102, reducing wear associated with using opposed tension between the opposed travel lines, thereby extending the service life of the system. As shown in the figures, travel lines 108 extend about a pulley 182 and extend through a passageway 170 formed in a tab 172 of weighted member 140.

Engagement of retention feature 162 with mating feature 164 is achieved by at least one (an opposed pair shown in FIG. 12) biasing device 168, such as a compression spring cartridge secured to cart frame 124 urging cam engagement member 142 toward support member 102. Biasing device 168 urges cam pivot member 144 along slot 166 toward a fully extended position 145B. However, opposed travel lines 108 are arranged such that during normal operation of the carriage, in which tension is maintained in the travel lines 108 to control the position of the carriage, the tension in travel lines 108 is also utilized to maintain biasing device 168 in a fully compressed position 145. Upon selectively controlled release of tension in travel lines 108, biasing device 168 is permitting to fully extend, urging cam pivot member 144 along slot 166, permitting position retention feature 162 and mating feature 164 of support member 102 to engage. Cam engagement member 142 is urged from operating position 174 to locking position 180. In locking position 180, retention feature 162 sufficiently engages mating feature 164 to ensure cam engagement member remains in locking position 180 until tension in travel lines 108 is reintroduced.

In response to a rapid loss of tension by one of travel lines 108 such as by failure of the travel line, cam engagement member 142 is urged into either first engagement position 176 or second engagement position 178, in which a portion of the periphery of cam engagement feature 142 contacts support member 102. However, in both first engagement position 176 and second engagement position 178, due to the rotation of cam engagement member 142 about cam pivot member 144, the position of cam pivot member 144 in an intermediate position 145A, and sizing of retention feature 162, retention feature 162 does not contact support member 102.

Referring to FIG. 4, in one embodiment, the control system 116 (see FIG. 1) controls the travel positioning mechanism(s) (see FIG. 1) to maintain the cam brake 120 in locking position 176 by producing an increased amount of slack at the second end 138 of the travel line 108, causing the weighted member 140 to actuate and rotate the cam engagement member 142 additionally about the cam pivot member 144. Alternatively, increased slack at the second end 138 of the travel line 108 occurs due to a rapid change in tension in one or more lines. In one embodiment, a top section 152 of the cam engagement member 142 is configured to frictionally engage the engagement surface 134 of the support member 102 surface to halt the carriage 104 and prevent it from moving along the support member 102. Thereafter, increasing tension at the second end 138 of the travel line 108 causes the weighted member 140 of the cam brake 120 to rotate back to the original position, thus rotating the cam engagement member 142 about the cam pivot member 144 in the opposite direction, disengaging the cam engagement member 142 from the support member 102 surface, and freeing the carriage 104 for movement along the support member 102.

Referring again to FIGS. 9-11, in one embodiment, removing tension at the second end 138 of the travel line 108 causes the weighted member 140 to rotate and drop, and the second lever assembly 241 to rotate about the lever pivot 244 until reaching the limit stop 249. The force from weighted member 140 against the limit stop 249 causes the cam engagement member 142 to rotate in a first direction and frictionally engage the support member 102. Similarly, removing tension at the first end 136 of the travel line 108 causes the weighted member 140 to rotate and actuate, and the first lever assembly 240 to rotate about the lever pivot 244 until reaching the limit stop 249. The force from weighted member 140 against the limit stop 249 causes the cam engagement member 142 to rotate in a second direction and frictionally engage the support member 102.

In one embodiment, such as shown in FIG. 1, the cam brake 120 includes a biasing device 167, such as a torsion spring (shown), compression spring or other suitable device using a resilient material having a retention force, the cam engagement member 142, the cart frame 124, and the lever pivot 244. Biasing device 167 releases the cam engagement member 142, allowing it to rotate when tension is removed from the second end 138 of the travel line 108. In one embodiment, the carriage includes the cart frame 124, cam brake 120, and the plurality of wheels 126 for positioning and repositioning a load 106.

Referring to FIG. 5, in one embodiment, the system 100 includes the support member 102, a first carriage 103, a second carriage 104, disposed in series along the support member 102, the travel line 108, a plurality of the lift lines 110, the travel positioning mechanism 112 (see FIG. 1), the lift positioning mechanisms 114 (see FIG. 1), and the control system 116 (see FIG. 1).

Referring to FIG. 6, in another embodiment, the system 100 includes a pair of the support members 102, a pair of the

carriages 104, each of the carriages 104 mounted on each of the support members 102, a load mount assembly 422, the travel line 108, the lift line 110, the travel positioning mechanism 112 and/or the lift positioning mechanism 114 (see FIG. 1), and the control system 116 (see FIG. 1). In one embodiment, a first set 425 of the wheels 126 engages a first support member 402, and a second set 426 of the wheels 126 engages a second support member 102.

Referring to FIG. 7, in one embodiment, the system 100 includes a pair of the support members 102, the carriages 104, the travel line 108, the lift line 110, at least one rotation line 560, a load rotation assembly 570, a rotation mechanism (not shown), the travel positioning mechanism 112 and/or the lift positioning mechanism 114 (see FIG. 1), and the control system 116 (see FIG. 1). Alternatively, in one embodiment, the carriage 104 includes the cart frame 124, the cam brake 120, the plurality of wheels 126, and a load rotation assembly 570. The load rotation assembly 570 is engaged by the rotation line 560 to rotate the load 106 along a substantially vertical axis relative to the carriage 104 when the carriage 104 is at rest.

Referring to FIG. 8, in an alternative embodiment, the system 100 includes the support member 102, the carriage 104, the travel line 108, the lift line 110, the travel positioning mechanism 112, and/or the lift positioning mechanism 114, and the control system 116. The carriage 104 includes the cart frame 124, a pair of the opposing cam brakes 120 arranged on opposing sides of the carriage 104, and a plurality of the wheels 126. In this embodiment, the lift line 110 is capable of being adjusted and oriented from either side, for example, by having a rotatable portion, thereby benefiting from including the opposing cam brakes 120 to respond to momentum in opposing directions. Likewise, in one embodiment, a plurality of cam brakes 120, for example, three cam brakes, four cam brakes, or more are included. In a further embodiment having a plurality of the cam brakes 120, each of the cam brakes 120 has a different load, thereby permitting additional control.

In one embodiment, a method of positioning the load 106 relative to support member 102 includes adjusting the relative position of the load 106 by adjusting the lift line 110 in conjunction with adjusting the travel line 108 in the system 100. In one exemplary embodiment, the method includes adjusting the relative position of the load 106 by increasing slack in the travel line 108 to position the engagement member in the positioning system 100.

While the invention has been described with reference to a preferred embodiment, it will be understood by those skilled in the art that various changes may be made and equivalents may be substituted for elements thereof without departing from the scope of the invention. In addition, many modifications may be made to adapt a particular situation or material to the teachings of the invention without departing from the essential scope thereof. Therefore, it is intended that the invention not be limited to the particular embodiment disclosed as the best mode contemplated for carrying out this invention, but that the invention will include all embodiments falling within the scope of the appended claims.

What is claimed is:

1. An engagement article capable of selectively restricting movement or securing a suspended load in response to a rapid change in tension in one or more lines, comprising:
a travel positioning mechanism operatively connectable to a carriage and at least one travel line, the travel positioning mechanism capable of positioning the carriage at intermediate positions along the travel line; and

the carriage operatively connectable to the at least one travel line and at least one lift line for supporting a load, the carriage operatively connectable to a first end and a second end of the travel line.

2. The engagement article of claim 1, comprising a lift positioning mechanism operatively connectable to the carriage.

3. The engagement article of claim 1, comprising a lift positioning mechanism operably connectable to a carriage; and the carriage operably connectable to at least one travel line and at least one lift line for supporting a load.

4. The engagement article of claim 2, wherein at least one of the travel positioning mechanism and the lift positioning mechanism is a manual device.

5. The engagement article of claim 2, wherein the lift positioning mechanism is operatively connectable to a first end of the lift line and the second end of the lift line is operatively connectable to the load.

6. The engagement article of claim 1, wherein the travel positioning mechanism includes an airflow interaction feature.

7. The engagement article of claim 1, wherein the travel positioning mechanism includes a weighted member and a cam engagement member pivotally connected eccentrically with respect to the center of gravity of the cam engagement member.

8. The engagement article of claim 7, wherein the travel positioning mechanism includes an airflow interaction feature formed in at least one of the weighted member and the cam engagement member.

9. The engagement article of claim 1, comprising a first travel positioning mechanism operably connectable to a carriage, the first travel positioning mechanism operatively connectable to at least one travel line; and a second travel positioning mechanism operatively connectable to at least one travel line, the second travel positioning mechanism positioned opposite the first travel positioning mechanism; wherein the carriage is operatively connectable to at least one lift line for supporting a load.

10. The engagement article of claim 1, comprising a first travel positioning mechanism operatively connectable to a carriage, the first travel positioning mechanism operatively connectable to at least one travel line; a second travel positioning mechanism operatively connectable to at least one travel line, the second travel positioning mechanism positioned opposite the first travel positioning mechanism; and wherein the carriage is operatively connectable to at least one travel line.

11. The engagement article of claim 10, wherein at least one of the first travel positioning mechanism and second travel positioning mechanism includes an airflow interaction feature.

12. The engagement article of claim 1, comprising a travel positioning mechanism operatively connectable to a carriage, the travel positioning mechanism operatively connectable at a first connection to at least one travel line; the travel positioning mechanism operatively connectable at a second connection to at least one travel line, the second connection positioned opposite the first connection; the carriage operatively connectable to at least one lift line for supporting a load; and

11

wherein the travel positioning mechanism having an air-flow interaction feature.

13. A system comprising an engagement article capable of selectively restricting movement or securing a suspended load in response to a rapid change in tension in one or more lines, the system further comprising:

a carriage operatively connectable to at least one lift line for supporting a load;

the engagement article comprising a travel positioning mechanism operatively connectable at a first connection to at least one travel line;

the travel positioning mechanism operatively connectable at a second connection to at least one travel line, the second connection positioned opposite the first connection; and

wherein the travel positioning mechanism having an air-flow interaction feature.

14. A process of selectively restricting movement or securing a suspended load comprising:

providing an engagement article in response to a rapid change in tension in one or more lines,

wherein the engagement article is a travel positioning mechanism operatively connectable to a carriage and a travel line, the carriage operatively connectable to at least one lift line for supporting a load and the travel line,

wherein the engagement article comprises a lift positioning mechanism operatively connectable to the carriage, wherein at least one of the travel positioning mechanism and the lift positioning mechanism includes an airflow interaction feature; and

actuating the engagement article.
